UNITED STATES PATENT OFFICE.

FRANK HEATH, OF NATIONAL CITY, CALIFORNIA.

SARDINE-TURNING APPARATUS.

1,373,812.

Specification of Letters Patent. Patented Apr. 5, 1921.

Application filed August 14, 1919. Serial No. 317,405.

To all whom it may concern:

Be it known that I, FRANK HEATH, a citizen of the United States, residing at National City, in the county of San Diego and State of California, have invented a certain new and useful Improvement in Sardine-Turning Apparatus, of which the following is a specification.

My invention relates to an apparatus for turning sardines so that they move head foremost and turn on to their backs and the objects of my invention are: first, to provide a device of this class which gives frictional contact with the sardines above and below 10 for turning them so that they move head foremost; second, to provide such an apparatus in combination with a means for turning said sardines on their backs; third, to provide such an apparatus which prevents 15 the sardines from rolling over and over when on an inclined plane and started sideways; fourth, to provide an apparatus of this class which tends to hold the sardines in their course head foremost and fifth, to 20 provide an apparatus of this class which is very simple and economical of construction, durable, easy to install, which is automatic in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a plan view of a unit of my device showing some sardines in position thereon; Fig. 2 is a sectional view through 2—2 of Fig. 1 and Fig. 3 is a sectional view through 3—3 of Fig. 1.

Similar characters of reference refer to similar parts and portions throughout the several views of the drawings.

The inclined surface member 1, supporting frame 2, support 3, supports 4, chains 5, grooves 6, and spray pipe 7 constitute the principal parts and portions of my sardine turning apparatus.

The inclined surface member 1 is preferably an inclined metallic member of sufficient inclination so that the sardines will move along said inclined surface by gravity

of sufficient speed that will not be easily retarded. This inclined surface is supported by the framework 2 which may be any particular construction desired (it being no 60 part of my present invention). The lower end of this surface member 1 is provided with a plurality of inclined, downwardly, differently and gradually curved bottomed chutes 6 with their walls converging toward 65 the lower end. At the sides of said apparatus are provided side members 1^a upon which is supported a cross bar 3 at the upper end and this cross bar 3 is provided with a plurality of posts 3^a to which one end 70 of the chains 5 are secured and mounted in the surface member 1 in certain spaced relation conforming with the space on the posts 3^a which is slightly shorter than the length 75 of the sardines to be turned are a series of posts 4 to which the other end of the chains 5 are secured. It will be here noted that these chains 5 are so supported and with sufficient slack in the chains so that they rest on the inclined member 1 and move 80 sidewise slightly. The upper surface of the inclined member 1 is preferably provided with a small quantity of water by means of the pipe 7 which is provided with a plurality of sprays for spraying the upper 85 surface of said inclined member.

Though I have shown and described a particular construction, combination and arrangement of parts and portions I do not wish to be limited to this particular construction, combination and arrangement but desire to include in the purview of my invention the construction, combination and arrangement substantially as set forth in 90 the appended claims.

The operation of my apparatus is as follows: The sardines are released in bulk form turned in miscellaneous directions on to the upper surface of the inclined member 1 and gravitate over the upper surface contacting with the upper surface of the member 1, and the chains 5 contact with the upper portion of the sardines and with their sides causing them to be turned head foremost by reason of the frictional engagement 95 of the sardines with the surface and chains. The frictional engagement of the chains being equal and the gravity of heads and tails being unequal cause them to gravitate to a position head foremost and said chains tend 100 to hold them in a given course. When they have reached the lower side of the surface

110

member 2 they are then moving head foremost and enter the grooves 6, the lower grooved surface of which changes gradually and the walls of the sides gradually converging cause the sardines to turn gradually on their backs while moving in the groove, the back and head being the heavy portion of the sardine, so that after they have moved sufficient distance in the chutes 6 they are positioned on their backs and ready for other action such as beheading, scaling, sizing and the like.

Having thus described my invention what I claim as new and desire to secure by Letters Patent, is:

1. In a sardine turning apparatus, an inclined imperforate member and a plurality of flexible sardine engaging and retarding members extending in the direction of inclination over the top surface of said inclined imperforate member.
2. In a sardine turning apparatus, an in-

clined imperforate member, a plurality of flexible sardine engaging and retarding members extending in the direction of inclination over the top surface of said inclined imperforate member and a perforate pipe extending along the upper edge of said inclined imperforate member for spraying the upper surface of said member.

3. In a sardine turning apparatus, an inclined member, a plurality of flexible engaging members extending in the direction of inclination over the top surface of said inclined member and a plurality of downwardly extending gradually deepening curved bottomed chutes with their walls converging downwardly connected therewith.

In testimony whereof I have hereunto set my hand at San Diego, California this 8th day of August, 1919.

FRANK HEATH.
